UNITED STATES PATENT OFFICE.

ONIS J. LENTZ, OF OAKLAND, CALIFORNIA.

FRictionless Rail Joint.

Application filed September 12, 1921. Serial No. 500,009.

To all whom it may concern:

Be it known that I, ONIS J. LENTZ, a citizen of the United States, residing at Oakland, in the county of Alameda and State of California, have invented certain new and useful Improvements in a Frictionless Rail Joint; and I do hereby declare the following to be a full, clear, and exact description of the invention, such as will enable others skilled in the art to which it appertains to make and use the same.

The invention relates to rail joints and aims to obviate the usual pounding of the rolling stock at the joints, to strengthen and brace the joint both vertically and laterally, to increase the bearing surface at the joint and lastly to obviate the formation of a gap between adjacent rail ends and provide in effect a continuous surface for sustaining the perpendicular pressure or load passing over the joint.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawing forming a part of the specification,

Figure 1 is a top plan view of a railroad rail joint embodying the invention,

Figure 2 is an end view thereof, the rail in section.

Figure 3 is a transverse section on the line $x-x$ of Figure 1,

Figure 4 is a detail perspective view of the base plate,

Figure 5 is a detail perspective view of the outer fish plate,

Figure 6 is a detail perspective view of the inner fish plate, and

Figure 7 is a detail perspective view of the spanner overlapping the joint formed between the abutting rail ends.

Corresponding and like parts are referred to in the following description and designated in the several views of the drawings by like reference characters.

The numeral 1 designates the abutting rail ends, each having a portion of the head cut away upon the outer side as indicated at 2. A spanner 3 fills the cut away portions

2 and overlaps the joint formed between the abutting rail ends 1 and is placed against the outer side of the web portions and rests upon the outer flange forming a portion of 60 the foot or base of the rails. The top and outer side of the spanner 3 are flush with corresponding parts of the head of the rails.

The base plate 4 is of a length and width to provide a substantial support for the 65 abutting rail ends and is supported upon the ties of the railroad. An integral flange 5 is provided near the outer edge and preferably forms a part thereof and has a longitudinal groove 6 upon its inner side adjacent the base plate 4. Channels 7 are formed in the upper side of the base plate 4 in position to come beneath the foot of the abutting rail ends so as to carry off moisture and provide for a circulation of air. A longitudinal 70 groove 8 is formed in the upper side of the base plate 4 near the inner edge thereof and inclines upwardly and outwardly to receive a corresponding flange at the lower edge of the inner fish plate as described more 75 detail hereinafter. The outer fish plate 9 is provided along its lower edge with a flange 10 which is adapted to engage over the outer flange forming a part of the foot of the rails. The outer portion of the flange 80 10 is adapted to enter the groove 6 of the flange 5 and thereby prevents vertical movement of the outer fish plate. Longitudinal ribs 11 formed upon the inner side of the fish plate 9 are adapted to engage the web 85 portions of the rail ends and act jointly with the inner portion of the flange 10 to prevent lateral movement of the abutting rails. The longitudinal ribs 11 and the inner portion of the flange 10 are cut away intermediate 90 their ends, as indicated at 12, to receive the spanner 3. The fish plate 9 is provided at its upper edge with an outwardly disposed flange 13 which is adapted to overlap and rest upon the upper edge of the flange 5. 95 The upper side of the flange 13 comes flush with the head or upper side of the rails so as to sustain the load passing over the joints and thereby provide an extended supporting rail surface. The upper side of the outwardly extending flange 13 inclines upwardly and outwardly to engage the outer portions of the wheels of the rolling stock when 100 the same passes over the joint.

The inner fish plate 14 engages the web 110 portions of the abutting rail ends and fits snugly between the inner portion of the head

and foot thereof. A longitudinal flange 15 at the lower edge of the fish plate 14 inclines inwardly and downwardly and makes a snug fit in the inclined groove 8 whereby 5 an interlocking connection is had between the fish plate 14 and the base plate 4 to prevent vertical displacement of said fish plate. It will thus be understood that both the inner and the outer fish plates have positive 10 interlocking connection with the base plate 4 to prevent vertical displacement thereof. The inner fish plate 14 has direct interlocking engagement with the base plate 4 through the instrumentality of the elements 15 8 and 15. The outer fish plate 9 has indirect interlocking connection with the base plate 4 through the flange 5 and the elements 6 and 10. The several parts such as the spanner 3, fish plate, flange 5 and rail ends having 20 registering openings to receive bolts 16 whereby they are made secure when assembled. The base plate 4 is provided in its longitudinal edge portions with openings 17 to receive spikes or other fastening means 25 (not shown) whereby to secure the base plate to the cross ties upon which it may be placed.

Having thus described the invention, what I claim is:—

1. In a rail joint, a base plate for receiving and supporting the abutting rail ends and provided in its upper side with a longitudinal groove which inclines upwardly and outwardly and a fish plate having a flange at its lower edge inclined inwardly and 35 downwardly to snugly fit the upwardly and outwardly inclined longitudinal groove of the base plate to form interlocking connection therewith.
2. In a rail joint, a base plate having an 40 upwardly extending flange provided upon its inner side adjacent the base plate with a longitudinal groove, said base plate being adapted to receive and support the abutting rail ends, and a fish plate disposed between 45 the abutting rail ends and the said flange and having a flange at its lower edge adapted to enter the groove of the flange formed with the base plate and form interlocking connection therewith.

3. In a rail joint, abutting rail ends having 50 portions of the head cut away at one side, a fish plate provided with inner linear projections having portions cut away opposite the cut away portions of the abutting rail ends and a spanner filling the space 55 formed by the said cut away portions and coming flush with the head of the rails to carry the load over the joint formed therebetween.

4. In a rail joint, a base plate having an 60 upstanding flange near one edge longitudinally grooved upon its inner side adjacent the plate and having a longitudinal groove in its upper side adjacent the opposite edge and laterally inclined in an upward and outward direction, abutting rail ends supported upon the base plate and having portions of the tread cut away upon the outer side, an outer fish plate disposed between the upstanding flange and the abutting rail ends 65 and having an outer flange at its upper edge overlapping and resting upon said upstanding flange and having its upper side flush with the tread of the rails and laterally inclined downwardly and outwardly a flange 70 at its lower edge with its outer portion engaging the longitudinal groove of said upstanding flange and having a longitudinal rib upon its inner side, said rib and the inner portion of the lower flange having portions cut away opposite the cut away portion of the abutting rail ends, a spanner filling the space formed by the said cut away portion and coming flush with the tread of 75 the rails to support the load in its passage over the joint formed therebetween and an inner fish plate fitting snugly between the head and foot of the abutting rail ends and having a flange at its lower end to engage the laterally inclined groove of the base 80 plate and form interlocking connection 85 therewith.

In testimony whereof I affix my signature in presence of two witnesses.

ONIS J. LENTZ.
